UNITED STATES PATENT OFFICE

HORACE K. HERNDON, OF GREENSBORO, NORTH CAROLINA

COOKING STOVE

Application filed April 18, 1929. Serial No. 356,143.

The present invention is directed to improvements in cooking stoves and is particularly designed for outdoor use.

The primary object of the invention is to provide a stove which is portable and can be readily assembled for use or disassembled for storage.

Another object of the invention is to provide a stove which has its top so constructed that vessels varying in size and shape can be effectively used for cooking purposes.

Another object of the invention is to provide a stove so constructed that wood or coal may be used for fuel and the heat directed upwardly so as to more effectively heat the top of the stove.

With these and other objects in view, this invention resides in the novel features of construction, formation, combination and arrangement of parts to be hereinafter more fully described, claimed, and illustrated in the accompanying drawings, in which:

Figure 1 is a perspective view of the stove.

Figure 2 is a longitudinal sectional view 25 through the same.

Figure 3 is a sectional view on the line 3—3 of Figure 2.

Figure 4 is a top plan view showing a modified form of lid arrangement.

Referring to the drawings, the numeral 30 1 designates the body of the stove which consists of side walls 2 and front and rear walls 3 and 4 respectively, the end walls being secured to the side walls by bolts 5.

35 The top 6 is secured to the flanges 7 of the end walls by bolts 8, said top having carried thereby, near its rear end, a thimble 9 for connection with a smoke pipe 10.

A baffle plate 11 is provided and has its 40 ends secured to the side walls 2 by bolts 12, said plate having a curved upper section 13, the upper edge of which is spaced from the top 6, as clearly shown in Figure 2 of the drawings.

45 The plate 11 has a flange 14 upon its front face which is directed toward a flange 15 carried by the inner face of the front wall 3. A grate 16 is provided and consists of sections 17, the ends of which are removably 50 mounted upon the flanges 14 and 15 to main-

tain the grate elevated. The grate is section- alized in order that it can be conveniently placed within or removed from the body of the stove, as the occasion may require.

The front wall 3 has formed therein a draft 65 opening 18 and a fuel feed opening 19, and associated with the respective openings are doors 20 and 21, said doors being preferably of the swinging type. The opening 18 also serves as a means for removing ashes from 60 under the grate and the draft can be conveniently regulated upon adjusting the door 20.

The top 6 is provided with a relatively 65 large opening 22, rectangular in contour, and in which is engaged a lid 23, said lid having an opening 24 therein for receiving the lid 25. The opening 24 and the lid 25 are also of rectangular formation. Obviously, the lids 23 and 25 can be removed in order that a vessel 70 of rectangular shape can be engaged over the opening 22, or, if a smaller similarly shaped vessel is used, the lid 25 is removed only.

In Figure 4, the lid 26 normally closes 75 the opening 22 and this lid differs from the lid 23 in that a circular opening 27 is provided in lieu of the rectangular opening, so that a ring lid 28 and a circular lid 29 may be used. In this manner, vessels of circular 80 formation can be placed over the openings, when desired.

It will be obvious that the heat from the fire will be directed by the curved section 13 of the plate 11 toward the top of the stove and 85 will assist the draft.

The stove may be made from cast iron or steel and since the parts thereof are bolted together it can be readily disassembled, when 90 desired.

A stove constructed in accordance with my invention can be placed directly upon the ground and in a yard and away from dwellings to prevent the likelihood of fires, and since vessels of various sizes and shapes can be used, the stove will prove extremely useful 95 for canning, preserving, and cooking stock foods.

From the foregoing, it is thought that the 100 construction, operation, and many advan-

tages of the herein described invention will be apparent to those skilled in the art, without further description, and it will be understood that various changes in the size, shape, proportion, and minor details of construction may be resorted to without departing from the spirit or sacrificing any of the advantages of the invention.

What is claimed is:

- 10 A portable stove for outdoor use comprising a body including front, back and side walls, a top extending over and closing the body and provided with an opening adjacent the rear wall, a thimble fitted in said opening,
- 15 a nest of lids fitted to an opening in the top to accommodate different shapes and sizes of cooking vessels, a plate within the body adjacent the rear wall and extending between the side walls and secured thereto and having
- 20 its upper portion curving rearwardly and terminating a short distance from the top, and a grate supported by the front wall and plate and extending between the side walls, the bottom of the body being open and
- 25 adapted to be closed by the ground upon which the stove is placed when in position for service.

In testimony whereof I affix my signature.

HORACE K. HERNDON. [L. S.]
